CASING AND DRILL PIPE PROTECTORS

Archer W. Kammerer, Jr., Fullerton, Calif., assignor to
Rotary Oil Tool Co., Huntington Park, Calif., a corporation of California

Application August 9, 1954, Serial No. 448,459

2 Claims. (Cl. 255—28)

The present invention relates to devices for protecting tubular drill strings during the rotary drilling of bore holes.

In the drilling of bore holes, rubber protectors have been mounted at spaced intervals on the exterior of strings of drill pipe, to prevent the latter from bearing against surface casing and other strings of casing in which the drill pipe is rotating. It is only desirable to have the protectors disposed along that length of the drill pipe located in the cased portion of the hole. Accordingly, in running drill pipe in the hole care must be exercised in accurately measuring the pipe, to insure that the pipe stands with protectors thereon will be incorporated in the drill string at the proper place, the protectors being located within the cased portion of the hole during the drilling operation.

Errors in measurement will result in the provision of inadequate protectors in the cased portion of the hole, or the disposition of rubber protectors in open hole, where the protectors are readily torn and inadvertently removed from the drill pipe by the open formation, which tends to restrict circulation of the drilling mud and possibly produces sticking of the drill pipe. Even with proper measurements, one or more of the protectors may be moved down below the cased hole and into open hole as drilling proceeds, producing the aforementioned hazards.

The present practice of providing protectors on drill pipe is a time consuming and costly one. Not only must careful measurements be made of the unprotected drill pipe sections to be run in the open hole, but the drill pipe sections fitted with protectors must be handled and stored separately. The protectors are placed on the drill pipe by special tools and must be cut off the drill pipe when the latter is to be used without protectors, or where a replacement protector is required.

Some bore holes are drilled by attaching a rotary drill bit to a string of well casing, rather than to drill pipe. Attempts to put rubber protectors on relatively large diameter drill casing would be comparatively costly, because of the size of the protectors, and such protected casing would be subject to the same disadvantages as drill pipe with protectors mounted thereon.

Accordingly, it is an object of the invention to provide a protective device for a tubular drill string that eliminates the need for measurements of the drill string sections as they are being run in the hole, and the special storing and handling of the sections to be used in the cased portion of the hole. The sections or stands of drill string can be run in the hole without regard to the length of the cased hole.

Another object of the invention is to provide a protective device for a tubular drill string, in which the device cannot be disposed below the cased length of the hole, thereby preventing damage to the protective device which would result were it disposed and used in open hole.

A further object of the invention is to provide a protective device for a tubular drill string that provides a

2

greatly increased bearing and protective service, increasing greatly the life of the protective device.

Yet another object of the invention is to provide a protective device that can be employed economically and with great effectiveness in conjunction with casing used as a drill string in drilling the bore hole.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claims.

Referring to the drawings:

Figure 1 is a longitudinal section, with parts shown in elevation, of a cased portion of the hole, embodying several forms of the invention, with a drill string disposed therein;

Fig. 2 is a greatly enlarged longitudinal section through a portion of the casing disclosed in Fig. 1, illustrating one form of protective device;

Fig. 3 is an enlarged longitudinal section through a portion of the casing shown in Fig. 1, disclosing another embodiment of the protective device.

As disclosed in the drawing, a string of casing 10, which may be surface casing, is disposed in a previously drilled bore hole 11. This casing string may constitute surface casing extending from the casing shoe 12, forming the lower terminus of the casing string, to the top of the well bore 11, and may include casing sections 13 threaded and coupled to each other. This string of casing 10 may be cemented in place by depositing cement in the annulus between it and the wall of the surrounding well bore 11.

A hole 14 is being drilled below the string of surface 10, or other cased portion of the hole 11. A tubular drill string 15 is run through the string of well casing 10, this tubular drill string having a rotary drill bit 16, of any suitable type, secured to its lower portion for operation upon the bottom 17 of the hole 14. The drill bit 16 drills away the formation material, which is flushed from the drilling region by means of the usual rotary drilling mud pumped down through the drill string 15 and out through fluid passages 18 in the drill bit, the drilling mud mixing with the cuttings and carrying them upwardly around the outside of the drill string 15, and through the annulus between the drill string and the surface casing 10 to the top of the well bore. The tubular drill string 15 may consist of sections of drill pipe secured to one another. However, as disclosed in the drawings, a string of drill casing is attached to the drill bit 16, the drill casing including casing sections 19 suitably connected to each other, as through use of intervening casing couplings 20.

It is desired to protect the drill string 15 and the casing 10 already disposed in the well bore by preventing the drill string from rubbing against the inner wall of the well casing 10 during the drilling operation. Heretofore, it has been the practice to mount rubber protective sleeves or devices on the drill string 15 at longitudinally spaced intervals, the rubber protectors being disposed preferably only upon that portion of the drill string that is located within the cased portion of the hole. The rubber protectors would bear against the inner wall of the casing 10 and prevent the steel drill string 15 itself from bearing against the latter, thus preventing wear between the drill string 15 and the casing 10.

In the present instance, the protective devices are not mounted on the drill string 15, but are incorporated in the

casing string 10 which has already been disposed in the hole, and in which the drill string is operating.

The protective devices shown in the drawings may assume different forms. Thus, a protective device may be incorporated in one or more of the casing couplings 21 that secure adjacent casing sections 13 together. Each casing coupling 21 is of a greater length than is usually provided, to form an extended coupling space 22 between the lower end 23 of the upper casing section 13 and the upper end 24 of the next lower casing section 13 in which a protective sleeve 25 may be disposed. This protective sleeve extends along substantially the entire length of the coupling space 22 and projects laterally into the casing string, the upper and lower ends 26, 27 of the sleeve preferably overlapping the inner walls 28 of the upper and lower casing sections, respectively, to avoid gaps in which the drill bit 16 might hang up or catch during longitudinal movement of the latter through the casing string 10. To facilitate guiding of the drill bit 16 and other portions of the drill string 15 past each protective device, the upper end 26 of the sleeve may flare, or be inclined, in an upward and outward direction, whereas the lower end 17 of the sleeve may flare, or be inclined, in a downward and outward direction. The ends of each sleeve 25 preferably terminate closely adjacent the inner walls 28 of the upper and lower casing section 13.

The inside diameter of the protective sleeve 25 is materially less than the inside diameter of the casing sections 13 themselves. However, such inside diameter of the sleeve is still substantially greater than the outside diameter of the drill string couplings 20, to insure proper annular clearance therebetween through which the drilling mud and cuttings can pass in an upward direction through the surface casing 10.

The protective sleeve 25 is preferably made of readily drillable material, such as rubber, brass, bronze, or aluminum, and is suitably secured to the coupling member itself. If the sleeve 25 is made of rubber or a rubber-like material, it can be secured to the coupling 21 by a proper vulcanizing operation. If it is made of brass or bronze, it can be attached to the coupling 21 through the use of brazing material 30.

The protective device 31 disclosed near the lower end of the casing string 10 is secured directly to a casing section 13 rather than to a casing collar. This protective sleeve, which may be made of any suitable material, such as rubber, brass, bronze or aluminum, as specified above, is secured to the inner wall 28 of a casing section, as through the agency of the vulcanizing or brazing operation referred to above, depending upon the particular material from which the protector sleeve 31 is made. This sleeve has a lesser wall thickness than the other form of protector sleeve 25, inasmuch as it is secured to the inner wall 28 of the casing section, and it is preferred that its inside diameter be substantially the same as the inside diameter of the other protective device 25. Similarly, its upper and lower ends 32, 33 flare in upward and downward directions, respectively, to facilitate movement of the drill bit 16 and the drill string 15 therethrough. As was described in connection with the other form of protective device, there will be sufficient annular clearance between the drill string 15 and the inner wall 34 of the protective sleeve 31 for the passage of drilling mud and cuttings therethrough.

The protective devices 25, 31 are incorporated in the surface casing 10 or other casing run in the hole, and through which the drill string 15 is to be run to drill a hole 14 below the lower end of the casing string, the protective devices being longitudinally spaced from one another and being disposed at suitable intervals along the length of the casing string 10. The drill string 15 is lowered through this casing 10, with the drill bit 16 at its lower end, the hole 14 below the casing string 10 being drilled to the desired depth. During the drilling opera-

tion, wear between the drill string 15 and the casing 10 is prevented, inasmuch as the drill string 15 can only move laterally into engagement with the protective devices 25, 31, and not into engagement with the casing string 10 itself. Since the protective devices are made of relatively soft material as compared with the steel of which the drill string 15 is composed, the latter will not be subject to wear. Any wear that might take place will occur on the protective sleeve or sleeves themselves. It is to be noted that the sleeves 25, 31 are of a comparatively large inside diameter and will have a relatively large wearing surface against which the drill string 15 can bear, thereby insuring long life of each protective device.

No problems are encountered in connection with the separate handling of sections or stands of drill pipe or drill casing 15 with protectors thereon, inasmuch as the cased portion 10 of the hole 11 itself is provided with the protectors. Since the drill string 15 has no protectors on it, there is no danger of protectors being disposed in the open hole 14 below the casing string 10, which might result in their being torn off, with resultant plugging or retarding of the circulation of the drilling mud in an upward direction around the annulus between the drill string 15 and the casing 10. The stands of drill string 15 can be racked and used without regard to the provision of protectors thereon, and it is unnecessary for careful measurements to be made when the drill string is being run into the hole, to insure the presence of drill string protectors at the proper location within the cased portion 10 of the hole. Actually, protective devices 25, 31 are disposed at the desired locations in casing 10 already disposed in the hole itself.

It has been proposed to drill a well bore 14 through use of casing 15 as a drill string rather than drill pipe. The casing would be run in the well bore and no round trips would ever be necessary, since the drill bit 16 is of a retrievable type that can be withdrawn through the drill casing 15 without the necessity for withdrawing the latter at all. A new bit can then be lowered through the well casing 15 and secured to its lower end. Accordingly, sections of drill casing 19 will be added at the top of the hole and the latter will be lowered in the hole 14 until the desired depth of hole has been produced. Thereafter, the drill bit 16 is removed and retrieved from the lower end of the casing 15 and the latter allowed to remain in the hole.

If it were necessary to provide protectors on the exterior of such a drill casing 15, the protectors would have to be incorporated thereon at the proper spaced intervals along its entire length, inasmuch as protectors disposed on the casing 15 within the previously cased portion 10 of the hole will eventually be moved down below the latter as drilling proceeds. Accordingly, a large number of rubber protectors would be operating in open hole, where the rubber protectors would eventually be torn as a result of bearing against the wall of the open hole 14. This large mass of torn rubber might completely stop the circulation of fluid, which would prevent continued drilling of the hole. Not only would such a condition be hazardous, but the number of protectors required would entail considerable expense.

By using an internal type of protector secured to the casing 10, applicant avoids the necessity for mounting an excessive number of protectors on his drill casing 15. The protectors are only required in the cased portion of the hole, and they can be supplied at the desired intervals along the casing length when the casing string 10 is run in the well bore 11.

Inasmuch as the protective devices 25, 31 are made of readily drillable material, they can be removed by use of a suitable diameter drill bit at any time, which might be necessary in the event an unrestricted bore through the casing string is desired. The drill bit will readily disintegrate the rubber, brass, bronze or aluminum from which the protector sleeves 25, 31 are made.

The inventor claims:

1. In combination: a string of casing disposed in a bore hole, including casing sections secured to each other, a pair of adjacent casing sections being secured to an intervening coupling, a readily drillable protective sleeve fixedly secured to said coupling and having an inside diameter substantially less than the inside diameter of said pair of casing sections to project laterally inwardly of the inner walls of said pair of casing sections, the upper and lower ends of said sleeve flaring in an upward direction and a 10 downward direction, respectively, and overlapping the walls of said pair of casing sections; a tubular drill string disposed in said casing string; and a drill bit attached to

said drill string and having an effective hole drilling diameter less than the inside diameter of said sleeve.

2. In a combination as defined in claim 1; wherein said sleeve is made of rubber vulcanized to said coupling.
